US0D1078044S

(12) **United States Design Patent** (10) **Patent No.:** **US D1,078,044 S**
(45) **Date of Patent:** **** Jun. 3, 2025**

(54) **SKIN TAG REMOVER**

(71) Applicant: **Xiaojun Liu**, Wafangdian (CN)

(72) Inventor: **Xiaojun Liu**, Wafangdian (CN)

(**) Term: **15 Years**

(21) Appl. No.: **29/865,291**

(22) Filed: **Jul. 18, 2022**

(30) **Foreign Application Priority Data**

Jul. 6, 2022 (EM) 009077746-0001

(51) **LOC (15) Cl.** **24-02**

(52) **U.S. Cl.**

USPC **D24/146**

(57) **CLAIM**

The ornamental design for a skin tag remover as shown and described.

DESCRIPTION

FIG. 1 is a perspective view of a skin tag remover showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines shown in FIGS. 1-7 illustrate portions of the skin tag remover that form no part of the claimed design.
